2 Sheets-Sheet 2

UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT.

BOLT-ACTION FIREARM.

Application filed October 22, 1925. Serial No. 64,077.

To all whom it may concern:

Be it known that I, THOMAS C. JOHNSON, a citizen of the United States, residing at New Haven, in the county of New Haven 5 and State of Connecticut, have invented a new and useful Improvement in Bolt-Action Firearms; and I do hereby declare the following, when taken in connection with the accompanying drawings, and the characters 10 of reference marked thereon, to be a full, clear, and exact description of the same, and which said drawings constitute part of this application, and represent, in—

Fig. 1 a view in right-hand side elevation 15 of a bolt-action firearm constructed in accordance with my invention.

Fig. 2 an enlarged, broken view of the receiver thereof, partly in side elevation and partly in central, vertical, longitudinal section. 20

Fig. 3 a view in rear elevation of the receiver and the one-piece combination bolt-retainer and ejector.

Fig. 4 a view in central, longitudinal section on the line 4—4 of Fig. 3, showing the receiver, combination bolt-retainer and ejector, and the forward end of the bolt, the rear end of the bolt being broken away.

Fig. 5 a view partly in rear elevation and 30 partly in transverse section on the line 5—5 of Fig. 4.

Fig. 6 a view in partly longitudinal, vertical, central section of the front end of the bolt, with the rear end thereof broken away.

Fig. 7 a view in side elevation of the combination bolt-retainer and ejector.

My invention relates to an improved bolt-action firearm of the class providing against the accidental removal of the bolt from the 40 arm when the positive bolt-stop of the arm has been withdrawn from action, or is out of play, the object being to produce an arm of the type described, of superior simplicity, durability, convenience, reliability, and 45 safety in use.

With these ends in view, my invention consists in a bolt-action firearm characterized by having a combined bolt-retainer and cartridge-ejector made in one piece and 50 shaped and positioned to prevent the accidental removal of the bolt from the arm

when the positive bolt-stop thereof has been withdrawn from action, or is out of play, but yielding to permit the withdrawal of the bolt from the arm when the user of the arm 55 exerts a special draft upon the bolt for that purpose.

My invention further consists in a bolt-action firearm characterized as above stated, having certain details of construction and 60 combinations of parts as will be hereinafter described and pointed out in the claims.

In carrying out my invention, as herein shown, I employ a receiver 10, comprising an approximately cylindrical forward end 65 11 having an internal thread 12 for the reception of the customary barrel 13 and further provided with locking-shoulders 14 for co-action with locking-lugs 15 formed integral with the forward end of an upturn and pull-back breech-bolt 16. The receiver 10 is further formed with a central bore 17 extending therethrough and a median loading-and-ejection opening 18. At its rear end it is formed with a bridge-portion 70 19. The bolt 16 reciprocates in the bore 17, its locking-lugs 15 sliding in grooves 20 and rotating one-quarter turn when the bolt is in its extreme forward position to co-act with the shoulders 14 aforesaid. The bolt 16 is 75 further provided with a central, longitudinal bore 21 for the reception of a firing pin 22, and formed on its underside with a longitudinally-extending series of predeterminedly irregularly shaped grooves 23, 24 and 25 85 lying in the same longitudinal plane and adapted to receive and co-act with a one-piece, combination bolt-retainer and cartridge-ejector 26, which, as shown in Fig. 5, is mounted in a slot 27 located in a central, 90 longitudinal plane passing through the axis of the receiver at an angle of about 30° from the vertical and opening from the lower left-hand side of the central bore 17 thereof. The said one-piece bolt-retainer and cartridge-ejector, by which my improvement is 95 characterized, is pivotally movable within certain limits upon a pin 28 and is held to project yieldingly into the central bore 17, by a coiled spring 29, as shown in Fig. 4. 100 The said coiled spring bears at one end against a lug 30 on the said one-piece mem-

ber 26 and at its other end against the bottom of a complementary bore 31 in the receiver 10, within which bore the spring is housed.

- 5 The firearm of my invention may be provided with any well known type of positive bolt-stop. In the arm shown for the illustration of my invention, its sear 35 is constructed and arranged to act to positively 75
 10 prevent the removal of the bolt from the receiver until it is drawn out of the way by an extra pull on the trigger 36 in the manner familiar to persons skilled in the art to which this invention relates, but my improved 80
 15 combined part 26 is equally applicable to guns having other well known forms of positive bolt-stops.

There are occasions when, for the insurance of safety, it is desirable to carry a fire-arm with the action open,—for example, in a hunting camp when there is more than one person present; on the firing-line of a target-shooting match; and on similar occasions. If this be done with the ordinary 95
 20 bolt-action firearm, and the positive bolt-stop thereof is accidentally withdrawn from its operative position, it not infrequently happens that the bolt drops by gravity alone out of the arm, and being naturally 100
 25 well covered with oil, picks up sand and dirt, rendering it necessary to take the bolt to pieces in order to make sure that all destructive grit is removed therefrom before 105
 30 it is replaced in the gun, and, in fact, before 110
 35 the arm can be safely used again.

The time required to recover the bolt, in case it falls out of the arm, and for cleaning it thoroughly before its reintroduction thereto, is often considerable, and seriously 115
 40 handicaps the owner or user of the gun. If, after recovering the bolt, the user of the arm does not take the time to thoroughly clean the bolt before putting it back in the arm, serious consequences are liable to follow, 120
 45 since the smallest particle of sand or grit may foul the system and cause it to jam and endanger the premature explosion of a cartridge in the barrel.

To avoid contingencies such as described, 125
 50 I have, as described, provided the arm with my improved, one-piece, combined bolt-retainer and cartridge-ejector, which takes the place of the separate members heretofore provided for the two functions indicated, 130
 55 in such a manner as to simplify the arm and make its action more reliable and safer.

In Fig. 4 I have shown the bolt of my improved firearm withdrawn just beyond the control of the sear 35, constituting the 135
 60 positive bolt-stop of the arm. My improved part 26 is formed with a rounded projection 32 on its upper edge, which co-acts with the forward portion of the bottom surface of the longitudinal groove 24 of the bolt 16 140
 65 in such a way as to yieldingly prevent the

bolt from escaping from the receiver 10 at any time when it is not positively prevented from falling out by the positive bolt-stop,—i. e., the sear 35. The power with which the bolt is prevented from escaping by my improved part 26 must be great enough to overcome the weight of the bolt under the action of gravity, but not so great but that the retaining action of the part may be readily overcome by a conscious grasp by the user of the arm upon the bolt itself, which, when pulled rearward, will overcome the retaining action of the improved part. The bolt 16, in order to separate completely 145
 70 from the receiver 10, must cam down the part 26 by riding over the projection 32 against the tension of the spring 29 and I have so proportioned the elements 24, 32, 30, and 29 that the weight of the bolt alone 150
 75 is insufficient to accomplish this result and thereby the accidental escape of the bolt 155
 80 from the receiver is obviated.

The other features of my improved gun constitute no portion of this invention and need not be here further described, other than to point out the facts that my improved safety-actuator 33 lies to the right of the center of the gun, obviating the danger of scraping the user's nose or cheek, and that the receiver and barrel 10 and 13 are attached to the stock portion by means of four centrally-located vertical screws 34, 37, 38, and 39, as shown in Fig. 2.

I claim:

1. A bolt-action firearm having a receiver, a breech-bolt located therein, a positive bolt-stop, and a one-piece, combined bolt-retainer and ejector, whereby the unintentional escape of the breech-bolt from the receiver is prevented when the positive bolt-stop is 160
 100 out of play.

2. A bolt-action firearm having a receiver, a reciprocative breech-bolt located therein, a positive bolt-stop, and a one-piece, spring-pressed, combined bolt-retainer and ejector co-operating with the breech-bolt and the receiver to yieldingly resist the escape of the breech-bolt from the receiver when the positive bolt-stop is out of play.

3. A bolt-action firearm having a receiver, a breech-bolt located therein and provided with a cam-surface, a positive bolt-stop, and a one-piece, combined ejector and bolt retainer co-operating with the cam surface to resist escape of the bolt from the receiver when the positive bolt-stop is out of play.

4. A bolt-action firearm having a receiver, a breech-bolt located therein and provided with a cam surface, a positive bolt-stop, and a one-piece, spring-pressed, combined ejector and bolt-retainer co-operating with the said cam surface of the said bolt to yieldingly resist escape of the bolt from the receiver when the positive bolt-stop is out of play.

5. A bolt-action firearm having a receiver,

a bolt located therein, the said receiver and bolt being each provided with one of a pair of complementary, longitudinal, radial slots, a positive bolt-stop, cam-surfaces in one of 5 said slots, and a one-piece, spring-pressed, combined bolt-retainer and ejector positioned in the other of the said slots to co-operate with the said cam surfaces, whereby the escape of the breech-bolt from the receiver is yieldingly resisted when the positive bolt-stop is out of play. In testimony whereof, I have signed this specification.

THOMAS C. JOHNSON.
